UNITED STATES PATENT OFFICE.

JOHN J. R. PATRICK, OF BELLEVILLE, ILLINOIS.

COMBINATION DENTAL TOOL.

SPECIFICATION forming part of Letters Patent No. 399,071, dated March 5, 1889.

Application filed August 31, 1888. Serial No. 284,275. (No model.)

To all whom it may concern:

Be it known that I, JOHN J. R. PATRICK, a citizen of the United States, and a resident of Belleville, in the county of St. Clair and State 5 of Illinois, have invented certain new and useful Improvements in Combination Dental Tools; and I do declare the following to be a full, clear, and exact description of the invention, such as will enable others skilled in the 10 art to which it appertains to make and use the same, reference being had to the accompanying drawings, and to letters or figures of reference marked thereon, which form a part of this specification.

Figure 1 of the drawings is a representation of this invention and is a side view. Fig. 2 is a view showing the other side, the rear portion of the pliers being broken away. Fig. 3 is a top view of the upper front portion. 20 Fig. 4 is a bottom view of the same.

The invention relates to improvements in combination-tools for dental purposes; and it consists in the construction and novel arrangement of parts, as hereinafter set forth.

The object is to combine with pliers several tools useful for dental purposes, so that such tools are ready at hand. The greater 25 number of said tools rely upon the pliers for operation.

Referring to the drawings, A designates the pliers, B shows steel cutting-blades for cutting wire and other metals, and C is a set-screw inserted through a threaded opening in one of the plier-jaws, designed to regulate the 35 closing of the jaws. A milled head, a, is provided, so that the screw can be operated with the fingers.

In dentistry metal posts are used for the purpose of securing an artificial crown to the 40 root of the tooth, and as the roots and canals of all teeth taper it is desirable not to drill a hole therein for the insertion of the tapered end of a metal post, and difficulty is found to secure the tapered posts in the root, as they 45 are at present not provided with a thread. For the purpose of forming a thread on such tapered posts, I provide the tapered screw-dies D at each side between the jaws. One pair of said dies may be smaller than the 50 other. To form a thread on the post, the tapered end thereof is held with a moderate pressure between the two sections of the dies, and the post is then turned to the left, or out

of the dies. The screw C may be adjusted to regulate the closing of the dies.

E is a taper-cutter on the outer side of one of the jaws for tapering the wire from which the post is formed before the thread is cut. The said device has a tapered opening, b, 60 longitudinally through it, and the top of said opening opens outward in V form in cross-section, as at c, and one edge, d, is sharpened and extends slightly over toward the center of the opening b. As the wire is inserted into the larger end of the opening b, it is to be 65 turned to the right against the cutting-edge, as it is pushed inwardly, and thus the wire or post is tapered by shaving a portion of it off.

F is a barb-cutter having its main portion threaded and inserted through a rearwardly-inclined opening in the jaw, as shown, and having its inner end sharpened in chisel form. The cutter is designed to barb delicate tapering wire used by dentists to clean out the dead 70 nerves from the teeth.

As the barb-cutter is threaded, it may be regulated to cut the barbs at an angle to the wire, if so desired, and the screw C may be adjusted to prevent the cutter from entering the wire too far.

Having described my invention, what I claim is—

1. In a dental tool, the pliers having tapered screw-dies D between the jaws, and the regulating set-screw C, substantially as specified.

2. In a dental tool, the combination of the pliers, the screw-dies, and the taper-cutter on one of the jaws, substantially as specified.

3. In a combination dental tool, the adjustable barb-cutter, substantially as specified.

4. In a combination dental tool, the pliers, the barb-cutter having a chisel point, and the set-screw, substantially as specified.

5. In a combination dental tool, the combination of the pliers, the set-screw, the cutter-blades, the screw-threaded dies, the taper-cutter, and the barb-cutter, substantially as specified.

In testimony whereof I affix my signature in presence of two witnesses.

JOHN J. R. PATRICK.

Witnesses:

FREDERICK SUNKEL,
PHIL. GASS.
